UNITED STATES PATENT OFFICE.

EUGENE PETERSON, OF NEW YORK, N. Y., ASSIGNOR TO WESTERN ELECTRIC COMPANY, INCORPORATED, OF NEW YORK, N. Y., A CORPORATION OF NEW YORK.

HIGH-FREQUENCY SIGNALING.

Application filed December 15, 1923. Serial No. 630,611.

To all whom it may concern:

Be it known that I, EUGENE PETERSON, a citizen of the United States of America, residing at New York, in the county of New York and State of New York, have invented certain new and useful Improvements in High-Frequency Signaling, of which the following is a full, clear, concise, and exact description.

10 This invention relates to high frequency signaling and particularly to high frequency transmission systems.

15 It is an object of the invention to produce efficient and improved modulation of a high frequency or carrier wave in accordance with a signal or other control wave.

20 Briefly, the invention relates to a transmission system in which a high frequency carrier wave is modulated in accordance with signal currents such as waves of speech frequency, thereby giving the high frequency oscillations a speech signal wave form. In such systems it is customary to suppress part 25 of the products of modulation, as for example, one side-band, or the unmodulated carrier and one of the side bands, by means of a wave filter, passing only the remaining portions of the wave to the high frequency line. At the distant station the received 30 signal may then be recast into intelligible form by a suitable demodulating apparatus.

35 A difficulty is encountered in transmission systems of the above type, however, in that a relative variation in either the filter constants or in the tuning elements of the oscillator shifts the portion of the wave that is suppressed and causes a confusion of the transmitted wave. This difficulty is overcome by the present invention.

40 In accordance with a feature of the invention, means is provided for transmitting a uniform modulated wave irrespective of relative variations in either the filter constants or the tuned oscillatory circuit.

45 This is accomplished by the provision of means whereby a variation in the filter constants produces a corresponding change in the transmitted side band so that the same portion of the modulated wave is transmitted at all times.

50 More specifically, the invention provides a modulator in which the usual tuning condenser of the oscillatory circuit is replaced by the capacity included in a filter which

serves both for selecting the side band and also to determine the frequency of the oscillator. In this system, a change in the filter constants such as to cause a change in the frequency of the oscillations, and consequently in the frequency of the modulated wave, also causes a corresponding change in the transmission range of the filter.

The invention is illustrated in connection with a modulator of the coupled plate or so-called constant current type comprising an oscillator preferably consisting of a vacuum tube of the audion type connected to an oscillatory circuit, and means for varying the voltage supplied to the oscillator in accordance with audio-frequency oscillations. The means for varying the voltage supply of the oscillator may consist of a vacuum tube of the audion type on whose input terminals the audio-frequency signals are impressed, the resultant amplified signals in the output circuit being impressed on the output circuit of the oscillating tube, thereby giving to the high frequency oscillations a speech signal wave form. Certain of the modulation components may be suppressed in the band filter which also furnishes the capacity of the oscillatory circuit, and the side band which it is desired to transmit may then be impressed on the transmitting terminals of a high frequency line circuit or, in the case of radio transmission, on a wireless antenna.

The drawing shows a diagrammatic illustration of a carrier transmission system embodying the invention.

Referring to the drawing, a microphone 1, representing an ordinary subscriber's telephone transmitter or any other low frequency transmitting device, is connected to a speech frequency line 2. The line 2 is coupled by means of a transformer 3 to the input of a vacuum tube 4 of the audion type. Plate 5 of this tube is connected through an anti-resonant circuit 6 with the plate 7 of an oscillator tube 8. Space current is furnished for both tubes from the source 9 through choke coil 10, which is designed to offer high impedance to the passage therethrough of currents of speech frequencies or higher frequencies. The input circuit of the oscillator tube 8 includes a coil 11 which is connected between the cathode 12 and control element 13 of this tube. A grid leak 14 and a blocking condenser 15 are also included in this circuit.

The coil 11 in the input circuit of the oscillator tube 8 is inductively related to the coil 16 which, together with the capacity reactance afforded by the band pass filter 17, comprises the tuned circuit of the oscillator. The filter 17 comprises series and shunt impedance elements and is preferably of the general type disclosed in G. A. Campbell Patent No. 1,227,113 of May 22, 1917. This filter may be adjusted for a given frequency of oscillation, and when so oscillating and speech frequency currents are produced in the low frequency line 2, the oscillations of the system will be varied in amplitude according to the speech frequency currents. The anti-resonant circuit 6 is tuned to the frequency of the carrier wave generated by the oscillator and consequently the carrier will not be passed to the speech amplifier tube 4. There is a speech frequency path from the plate circuit of the speech amplifier tube 4, however, to the oscillator tube, and consequently the speech currents amplified in the tube 4 are impressed on the output circuit of the oscillator tube 8 to modulate the carrier wave. The filter 17 while serving to determine the frequency of the oscillator may, at the same time, be adjusted to suppress certain of the products of modulation and to pass others to the line for transmission to a distant station, not shown. Heretofore, since the filter for suppressing part of the modulated wave and the tuning elements for the oscillator have been separate units, a relative variation in either the filter constants or the tuning would shift the portion of the wave to be suppressed. According to the present invention, if there is a variation in the oscillator frequency due to changes in the filter constants, the transmitted band shifts accordingly so that the portion of the modulated wave transmitted remains the same. By means of this arrangement, the filter 17 may be designed to have the proper capacity and proper impedance so that the frequency of the oscillator is maintained at a point near the edge of the side band that is to be transmitted. This enables one side band or one side band and the carrier to be suppressed and the other side band with or without the carrier, to be transmitted. In a particular system employed by applicant, for a carrier frequency of 8000 cycles, the side band transmitted was 6000 to 8000 cycles. In this case, the inductance of the coil 16 was 30 millhenrys and the capacity reactance of the filter 17 was so proportioned in accordance with the above mentioned Campbell patent as to resonate with the coil at the carrier frequency, while the filter passed selectively the band from 6000 to 8000 cycles, as mentioned above.

While for the purpose of illustration the

invention has been described in connection with a carrier line signaling system, it will be understood that it is equally applicable to radio signaling systems.

The invention may also be embodied in forms other than that herein shown and described without departing in any way from the spirit of the invention, the scope of which is defined in the appended claims.

What is claimed is:

1. In a signaling system, means for independently generating two waves, means for modulating one of said waves in accordance with the other to produce side bands lying above and below the frequency of said modulated wave, and common means for controlling the frequency of the wave to be modulated and for suppressing the side band lying to one side of said wave.

2. In a signaling system, means for generating a high frequency wave, means for modulating said wave in accordance with audio-frequency currents to produce side bands lying above and below said high frequency wave, and a tuned circuit for said generator including means for suppressing the side band lying to one side of said wave.

3. In a signaling system, means for modulating a high frequency wave in accordance with speech currents to produce side bands lying above and below the frequency of said wave, an oscillation generator, and common means for determining the frequency of said generator and for suppressing the side band lying to one side of said wave.

4. In a signaling system, means for modulating a high frequency wave in accordance with speech currents, a generator of high frequency waves, and a filter in the oscillatory circuit of said generator adapted to determine the frequency of said generator and to selectively transmit the products of modulation.

5. In a transmission system, means for modulating a high frequency wave in accordance with speech currents to produce side bands lying above and below the frequency of said wave, means for impressing currents of speech frequency upon said modulating means, and means to determine the frequency of the wave to be modulated and to suppress the side band lying to one side of said wave.

6. In a transmission system, means for modulating a high frequency wave in accordance with speech currents, a circuit for impressing currents of speech frequency upon said modulating means, and a filter in the output of said system adapted to determine the frequency of the wave to be modulated and to selectively transmit the products of modulation.

7. In a transmission system, a pair of vacuum tubes having their plates coupled

together, circuits for independently supplying carrier oscillations to the input circuit of one of said tubes and speech frequency oscillations to the input circuit of the other tube, and a band filter in the oscillatory circuit of the first mentioned tube adapted to determine the frequency of said tube and for selectively transmitting the products of combined carrier and speech frequency currents.

8. In a transmission system, a pair of vacuum tubes having their anodes coupled together, circuits for independently supplying carrier oscillations to the input circuit

of one of said tubes and speech frequency oscillations to the input circuit of the other tube, a common source of substantially constant current for supplying space current to said tubes, and a band filter associated with the first mentioned tube adapted to determine the frequency of said tube and for selectively transmitting the product of the combined carrier and speech frequency currents.

In witness whereof, I hereunto subscribe my name this 12 day of December A. D., 1923.

EUGENE PETERSON.
